UNITED STATES PATENT OFFICE.

ROBERT T. BURDETTE, OF CHICAGO, ILLINOIS.

METAL RAILROAD TIE.

Application filed June 23, 1924. Serial No. 721,718.

To all whom it may concern:

Be it known that I, ROBERT T. BURDETTE, a citizen of the United States, and resident of Chicago, county of Cook, and State of Illinois, have invented certain new and useful Improvements in Metal Railroad Ties, of which the following is a specification, and which are illustrated in the accompanying drawings, forming a part thereof.

10 This invention relates to metallic railway ties and means for positioning the rails thereon.

One of the objects of the invention is the provision of a metallic railway tie having a 15 suitably cushioned seat for the rail with new and improved means for securing the cushioning members in position beneath said rail.

Another object of the invention is the provision of a metallic tie having new and improved positioning and fastening members for adjustably securing the rails to the tie.

Other objects of the invention are the provision of a metallic tie with new and improved means for anchoring the tie, and for 25 adjustably securing the rails to the tie for compensating for wear of the rails, and so arranging the parts that the tie will be cheap to manufacture, easily assembled and 30 placed in position, that is efficient in use, and that is not likely to become broken or get out of order.

Other and further objects and advantages of the invention will appear from the following description taken in connection with the accompanying drawings, in which—

Fig. 1 is a side elevation of a portion of a track showing my invention in position thereunder;

40 Fig. 2 is a section on line 2—2 of Fig. 1;

Fig. 3 is a plan view of the construction shown in Fig. 1;

Fig. 4 is a section on line 4—4 of Fig. 3;

45 Fig. 5 is a cross section of the track and road bed showing the invention in position;

Fig. 6 is a side elevation of the construction shown in Fig. 5;

Fig. 7 is a perspective view of a positioning block;

50 Fig. 8 is a perspective view of an insulating member;

Fig. 9 is a perspective view of one of the wedges;

55 Figs. 10 and 11 are elevational views of the key member;

Figs. 12 and 13 show modified forms of positioning blocks; and

Fig. 14 is a cross section of a curved road bed showing the application of the wedges disclosed in Figs. 7 and 12, for varying the 60 gauge of the track.

On the drawings the reference character 10 designates a rail of any usual or well known construction employed as a track in railroads and the like. Each rail is adapted 65 to be supported in a series of rail seats or chairs 11, each of which comprises a base 12 and an upwardly extending recess or channel 13 within which the rail 10 is disposed. The channel 13 is formed by the floor 14 70 and the upwardly extending side walls 15 and 16 spaced apart a greater distance than the width of the foot flange 17 of the rail 10.

The side walls 15 and 16 are provided with recesses or pockets 18 and 19 terminating 75 at their upper ends in grooves 20 and 21 for the reception of rail positioning blocks as will presently appear.

Suitable means are provided for positioning the rail within the seat 11. As shown, 80 positioning blocks 22 and 23 are employed for this purpose, one on each side of the rail. The blocks shown in Figs. 1 to 8 inclusive are duplicates of each other and each is provided with a straight back 220 for engaging 85 the bottom wall of the recess 18 or 19. Its upper end is reduced to engage the groove 20 or 21. A lateral extension 24 provided with a lower angular surface forming a shoulder 25 and a downward extension 26 90 is adapted to extend over and downward alongside the foot flange 17 for preventing lateral, vertical or turning movement of the rail. Preferably the side walls are extended upwardly as far as is consistent with proper 95 construction in order that the blocks 22 and 23 may be extended to provide as great a leverage as possible for preventing turning of the rail within the seat.

Suitable means, such as the members 27, 100 of insulating material, may be interposed between the flange 17 and the angular surface 25 of the blocks 22 and 23. This material not only insulates the rail from the blocks and side walls of the seats, but also 105 acts as cushioning members thereby prolonging the life of the rails and their seats. The members 27 are preferably provided with retaining flanges 28 and 29 at each end thereof to prevent their displacement. 110

In order to firmly secure the foot flange 17 against the shoulders 25 of the blocks 22 and 23, suitable wedge means 30 are employed. Preferably two wedges are used for each seat, the wedges being duplicates. The thin portions of the wedges overlap and they are adapted to be driven toward each other for forcing the flange 17 upwardly against the shoulders 25.

10 In order to deaden the vibration incident to the passage of trains along the track, and at the same time afford a resilient as well as an insulating support, these wedges are of suitable yielding insulating material, preferably fibrous, such as wood.

The continued vibration of the rails, their creeping movement and the like incident to the movement of traffic, especially on curves, tends to cause the loosening or displacement 20 of the wedges. It is desirable, therefore, to provide means for preventing loosening or relative movement, of the blocks. In the form of the device selected to illustrate one embodiment of the invention, the side walls 25 are provided with guides or recesses 31 and 32 at diagonally opposite points in which the backs of the retaining keys 33 are adapted to engage. The inner edges of the keys 33 are V-shaped and are provided with serrations as at 34. The upper end of the key may be provided with an outwardly extending portion forming a head 34^a for removing the key. The heads 34^a are adapted to engage notches 57 at the upper ends of the 30 guide ways or recesses 31 and 32 for preventing turning movements of the keys. The notches are sufficiently deep to permit the heads 34^a to be driven below the flange 17 whereby the rail may be adjusted over said 40 head without contacting the same. The lower end of the key may be tapered as at 35 to facilitate its entrance between the side wall and the wedges.

45 After the wedges have been driven beneath the rail, the keys are driven home thus forcing the serrations to enter the wedges and at the same time forcing the wedges to a position at an angle to the rail. The keys being arranged diagonally across the rail seat, each engages the thick portion of a wedge and they cooperate to turn the wedges in the same direction to an oblique position. By this arrangement the wedges are not only locked by the keys against longitudinal movement but, being turned so that the grain of the wood is oblique to the rails the force will be applied diagonally to the fiber of the wedges and the friction of the parts will tend to prevent the separation of the 55 wedges. This is considered an important feature of the invention. Furthermore, the sides of the rail seat are duplicates and it is immaterial in assembling the device which side is arranged outwardly of the rails.

60 65 Suitable means are provided for rigidly

connecting together the rail seats at each side of the track. As shown, a metallic channel bar 38 is employed for this purpose. A seat is adapted to be rigidly attached to the bar at each end thereof, the whole forming a metallic tie.

The base 12 of the seat is provided with laterally extending feet or flanges 39 which are adapted to engage the web 41 of the channel bar 38. The rail seats are connected to the channel bar by any suitable means, such as the rivets 42 extending downwardly through the feet 39, the web 41 and the transverse members 42^a. The transverse members 42^a not only assist in rigidly securing the rail seats to the channel bar, but also perform the function of cleats to prevent the longitudinal movement of the tie when the same has been placed in position on the ballast or road bed.

70 75 80 85 Suitable webs 43 are adapted to connect the feet 39 with the sides of the rail seat opposite the pockets or recesses 18 and 19 for bracing that portion of the seats.

In railway construction it is necessary to vary the gauge of the track by increasing the distance between the rails on curved tracks, as shown in Fig. 14. In the present construction provision is made for varying the gauge without varying the distance between the rail seats of the tie. Each rail seat is made of sufficient width to permit a limited lateral adjustment of the rail within the seat. The adjustment is preferably obtained by employing positioning blocks of different thicknesses. As shown in Fig. 12 the block 55 is of greater thickness than the block 22 which is the one usually employed on straight-way tracks. A block 56 for co-operating with the block 55 is shown in Fig. 13 of the drawing. This block is of less thickness than the block 22.

90 95 100 105 110 115 120 Various arrangements of the blocks 55, 56 and 22 may be had. As shown in Fig. 14 the rail 10 at the left of said figure is positioned within the seat by the blocks 22 and 23 while at the right of said figure the rail is positioned within the seat by means of the blocks 55 and 56. The block 55 being the thicker one is placed on the inner side of the rail whereby the gauge of the rails will be increased over that shown in Fig. 5.

125 While I have shown the outer rail of the curve as being positioned in the seat by means of the blocks 55 and 56 it is understood that the inner rail may be positioned by these blocks and the blocks 22 of medium thickness be used on the outer rail. As the rails become worn it may become necessary to move the rails closer together. This may be accomplished by an arrangement of the blocks as will be obvious to any one skilled in the art.

130 The rail seats may be formed in any suitable manner, but preferably each is a sepa-

rate integral casting. They are interchangeable, which greatly facilitates the assembly of the parts. The seats are of sufficient width to receive the larger rails and by employing wedges of different thicknesses the smaller as well as the larger rails may be rigidly secured within the seats. When the parts are assembled, a metallic tie is produced which may be embedded in the ballast or roadbed in the usual manner, and when in position will be more firmly held than the wooden ties now in common use.

It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:—

1. In a device of the class described, a seat for receiving a rail of a railway track, blocks for securing said rail within said seat, said blocks being of different thicknesses whereby said rails may be adjusted laterally in said seat by interchanging the same, and wedging means beneath said rail.

2. In combination, a pair of rail seats, means for spacing said seats apart, a rail in each seat, blocks for positioning said rails in said seats, said blocks being of different thicknesses, whereby the gauge of the track may be varied by interchanging the blocks, resilient members between said rails and said seats, and means for locking said members in position.

3. In combination, a rail seat, a rail within said seat, means for positioning said rail within said seat, cushioning means between said seat and rail, and means insertable after said rail is fastened in position in said seat for locking said cushioning means in position beneath said rail.

4. In combination, a metallic tie comprising a connecting member, a rail seat secured to each end of said connecting member, said seats being interchangeable and each being a separate integral cast structure and having a groove therein and a key slidably

mounted in said groove, said key having serrations on one side thereof.

5. In combination, a rail seat, a rail within said seat, means for positioning said rail within said seat, wedges between said rail and seat, and means for holding said wedges at an angle to the axis of said rail.

6. In combination, a metallic tie comprising a rail seat at each end of said tie, each seat comprising side walls having recesses therein terminating in grooves at their upper ends, a rail in said seat, blocks at each side of said rail having laterally extending portions for engaging the foot flange of said rail, wedges beneath said flange, and key members in channels in the side walls of said seats for securing said wedges in position in said seat.

7. A metallic tie, comprising a channel bar, a rail seat secured in the channel at each end of said bar, cleats extending across said bar beneath each seat, and means for securing said seat, bar and cleats together.

8. In combination, rail seats, rails secured in said seats, wedge-shaped resilient members between said rails and seats, means for locking said members in position beneath said rails, and means for preventing movement of said last named means.

9. In combination, a rail tie provided with a rail seat adjacent each end thereof, each seat provided with key ways diagonally arranged with notches adjacent the upper ends of said keyways, a rail secured in each seat, wooden wedges in said seats beneath said rails, and serrated keys in said guide ways for engaging said wedges for holding the same in position, said keys being provided with outwardly extending heads for engaging said notches.

10. A seat for a rail of a railway track comprising a base and upwardly extending side walls spaced apart for the reception of a rail of a railway track, blocks adapted to interlock with said walls for positioning a rail within said seat, and means associated with one of said walls and adapted to retain a supporting member between said rail and said base.

ROBERT T. BURDETTE.
